UNITED STATES PATENT OFFICE.

EDWARD A. CULBERTSON, OF WICHITA, KANSAS.

PUMP.

Application filed December 12, 1921. Serial No. 521,731.

To all whom it may concern:

Be it known that I, EDWARD A. CULBERTSON, a citizen of the United States, residing at Wichita, in the county of Sedgwick and 5 State of Kansas, have invented a certain new and useful Improvement in Pumps, of which the following is a specification.

My invention relates to improvements in pumps.

10 It is particularly well adapted for use in pumping water or oil from deep wells, and is of the type in which the pump barrel is located adjacent to the bottom of the well, and in which the piston reciprocates in the 15 pump barrel and is lifted by a rod or rods joined together and extending to the surface of the ground.

One of the objects of my invention is to 20 reduce to a minimum the pressure against the lower end of the piston when the latter descends, thereby eliminating jerking and buckling of the rod and increasing the capacity of the pump.

25 A further object of my invention is to provide a maximum capacity of pump casing with a minimum cross sectional area, and which has a substantially smooth cylindrical form devoid of large laterally extending projecting pipes or portions.

30 Still another object of my invention is to provide a novel arrangement of check valves which permits of a minimum diameter of casing.

35 A further object of my invention is to provide a chamber at the bottom of the casing for the reception of sediment, so that the latter will not clog or interfere with the proper operation of the standing intake valve.

40 The novel features of my invention are hereinafter fully described and claimed.

In the accompanying drawing which illustrates the preferred embodiment of my invention,

45 Fig. 1 is a central vertical sectional view of my improved pump.

Fig. 2 is an enlarged cross section on the line 2—2 of Fig. 1.

Fig. 3 is an enlarged cross section on the 50 line 3—3 of Fig. 1.

Fig. 4 is an enlarged cross section on the line 4—4 of Fig. 1.

Fig. 5 is an enlarged cross section on the line 5—5 of Fig. 1.

55 Fig. 6 is an enlarged cross section on the line 6—6 of Fig. 1.

Similar reference characters designate similar parts in the different views.

In the form shown in the drawing, the casing comprises the following described parts. 60 The lower end of the casing is provided with a coupling 1 having a threaded upper end in which is fitted the lower end of a pipe 2, the upper end of which has threaded engagement with the lower end of an intermediate section 3, preferably a casting, the upper end of which has threaded engagement with the lower end of a pipe 4, the upper end of which has threaded engagement with the lower end of a coupling 5, the 70 upper end of which is adapted to have threaded engagement with the lower end of piping 6, which extends to the surface of the ground.

The lower end of the coupling 1 is adapted 75 to have threaded engagement with the upper end of piping 7 which extends to and rests on the bottom of the well.

A vertical pipe 8 has its lower end fitted in the threaded lower end of the coupling 1 and 80 extends upwardly in and is spaced apart from the pipe 2, and which forms with the pipe 2 and coupling 1 a chamber for the reception of sediment.

The intermediate section 3 of the casing 85 is provided with a longitudinal partition 9, the upper and lower ends of which are enlarged and respectively connect with opposite inner walls of the section 3.

The pipe 8 serves as an inlet passage for 90 the casing and has mounted on its upper end the casing 10 of a standing intake check valve provided with an upwardly opening ball valve 11.

A vertical pump barrel 12 is mounted centrally in and spaced apart from the pipe 4 and has its lower end fitted in a threaded hole in the upper end of the partition 9. The upper end of the barrel 12 is fitted between internal lugs 13 in the coupling 5. 95

The partition 9 forms in the section 3 two longitudinal passages 14 and 15, the passage 14 communicating at its upper end with the lower end of the pump barrel 12 and its lower end communicating with the interior 105 of the pipe 2. The space 16 between the pump barrel 12 and the pipe 4 and coupling 5 communicates at its upper end with the upper end of the pump barrel 12. The space 16 at its lower end communicates with 110 the upper end of the passage 15. The lower end of the passage 15 is threaded and has

fitted in it the casing 17 of a standing check valve provided at its upper end with an upwardly opening ball valve 18.

The lower end of the casing 17 is provided with a socket 19 adapted to receive a wrench for screwing the casing into or removing it from its operative position. The side walls of the casing 17 is provided with perforations 20 which communicate with the interior of the pipe 2.

The perforations 20, longitudinal opening through the casing 17, passage 15 and spaces 16 form a by-pass, which at its upper end communicates with the upper end of the pump barrel 12, and which at its lower end, through the intermediacy of the pipe 2 and passage 14, communicates with the lower end of the pump barrel 12.

Reciprocal in the pump barrel 12 is a piston 21, the upper end of which is attached to the lower end of an operating rod, or series of jointed rods, 22, which extends through the piping 6 to the surface of the ground, where the rod is connected to and operated by any usual type of pump operating means, not shown, by which the rod and piston and the column of oil or water carried by the piston are lifted.

The piston 21 is provided therethrough with a longitudinal port 23 adapted to be closed by an upwardly opening ball check valve 24.

In the operation of the pump, when the piston ascends, liquid will be drawn by suction upwardly through the piping 7, pipe 8, and past the valve 11 into the pipe 2, and the column of liquid on the piston 21 will be lifted.

When the piston descends, the valve 11 will be closed and the valve 24 will be opened, and liquid will pass upwardly into the barrel 12 above the piston 21 through the port 23. The sudden descent of the piston would, ordinarily, be resisted by the liquid below the piston, due to the resistance offered to the passage of liquid through the relatively small port 23. In my improved construction, the piston in descending will force liquid below it out of the passage 14 and pipe 2 through the perforation 20, thence upwardly through the valve casing 17, past the valve 18, thence through the passage 15, and space 16, into the upper end of the pump barrel 12.

In order to reduce to a minimum, the resistance offered by the liquid against the downward movement of the piston, the smallest cross sectional area or effective opening in the by-pass is substantially as great as the cross sectional area of the piston 21, outside of the port 23. By means of this construction, the effective cross sectional area of the by-pass and of the port 23 is substantially as great as the cross sectional area of the inside of the pump barrel

12. The piston will, therefore, be dropped freely through the pump barrel to the lower end of its descending stroke.

Bending or buckling of the rod 22 is thus prevented, the piston will drop with maximum speed and a maximum of pumping capacity will be afforded.

It will be noted that the three check valves 11, 18 and 24 are located in substantial vertical alignment with each other. By means of this arrangement, a minimum of diameter and a maximum of capacity is obtained. The casing is substantially cylindrical and is devoid of large lateral projections and of external piping.

This construction also affords cheapness in manufacture, strength, and a construction which is not liable to get out of order.

I do not limit my invention to the structure shown and described, as many modifications, within the scope of the appended claims, may be made without departing from the spirit of my invention.

What I claim is:—

1. In a pump of the kind described, an outer vertical casing having an intermediate section provided with two longitudinal passages, a pump barrel having its lower end fitted in and communicating with one of said passages, a check valve having a casing fitted in and communicating with the other of said passages, the last named passage from said check valve communicating at all times with said pump barrel at the upper end thereof, an intake standing check valve in said casing below said two passages, and a piston reciprocal in said barrel, substantially as set forth.

2. In a pump of the kind described, an outer vertical casing having an intermediate section provided with two longitudinal passages, the upper end of one of said passages being screw-threaded, a vertical pump barrel having its lower end fitted in said threaded passage, the lower end of the other passage being screw-threaded, a check valve having a valve casing fitted in the threaded end of said last named passage, said last named passage communicating with the upper end of said pump barrel, and an intake standing check valve in said casing below said two passages, and a piston reciprocal in said barrel and having a longitudinal port and a check valve controlling said port, substantially as set forth.

3. In a pump of the kind described, a vertical pump casing adapted to be inserted in a well casing, a standing intake check valve in said pump casing, a vertical pump barrel in said pump casing, the pump casing having within it a by-pass which communicates at its ends respectively with the pump barrel, a piston reciprocal in the pump barrel between the ends of said by-pass, and a check valve in said by-pass, the by-pass

from the check valve in the by-pass being at all times in open communication with the pump barrel above the piston, substantially as set forth.

5 4. In a pump of the kind described, a vertical pump casing adapted to be inserted in a well casing, a standing intake check valve in said pump casing, a vertical pump barrel in said pump casing, the pump casing having within it a by-pass which communicates at its ends respectively with the pump barrel, a piston reciprocative in the pump

barrel between the ends of said by-pass, the piston having a longitudinal port and a check valve controlling said port, and a 15 check valve in said by-pass, the by-pass from the check valve in the by-pass being at all times in open communication with the pump barrel above the piston, substantially as set forth. 20

In testimony whereof I have signed my name to this specification.

EDWARD A. CULBERTSON.
